CLAIM

The ornamental design for a facade for a dry cleaning machine, as shown and described.

DESCRIPTION

FIG. 1 is a front elevational view of a facade for a dry cleaning machine showing my new design; the rear is plain and unornamented;

FIG. 2 is a right side elevational view thereof; and

FIG. 3 is a left side elevational view thereof.

FIG. 1.

FIG. 2.

FIG. 3.
